(57) CLAIM

The ornamental design for the cookware cover, as shown and described.

DESCRIPTION

FIG. 1 is a perspective top and side of a cookware cover showing the new design;

FIG. 2 is a side elevation view thereof showing the cover positioned on an article of cookware;

FIG. 3 is a side elevation view thereof.

FIG. 4 is a top plan view thereof;

FIG. 5 is a bottom plan view thereof; and,

FIG. 6 is a side view in cross-section of the cover of FIG. 4 taken through the lines 6—6.

The ornamental design which is claimed is shown in solid lines in the drawings. The broken lines in the drawings are for illustrative purposes only and form no part of the claimed design.
